D. BEALS.
CAR COUPLING.# UNITED STATES PATENT OFFICE.

DAVID S. BEALS, OF ADRIAN, MICHIGAN, ASSIGNOR TO HIMSELF AND
JOHN J. YOUNG, OF SAME PLACE.

IMPROVED CAR-COUPING.

Specification forming part of Letters Patent No. 80,117, dated July 21, 1868.

To all whom it may concern:

Be it known that I, DAVID S. BEALS, of Adrian, in the county of Lenawee and State of Michigan, have invented a new and useful Improvement in Car-Couplings; and I do hereby declare the following to be a full, clear, and exact description thereof, reference being had to the accompanying drawings, which are made a part of this specification.

The subject of my invention is a car-coupling in which the coupling medium proper consists of a pair of spring-clutches having barbed opposing ends, and so arranged as when the cars are brought together to couple automatically, and when thus coupled to be incapable of separation except by the appointed means, a novel and simple construction of buffer being employed to prevent any deleterious results of the concussion of the cars in coupling or by accident.

In the drawings, Figure 1 is a sectional view of portions of the contiguous ends of a pair of cars having my improved buffer and coupling applied on the horizontal plane indicated by the line $x x$; Fig. 3. Fig. 2 is an under-side view with certain parts removed. Fig. 3 represents a longitudinal section on the line $y y$, Fig. 2, and a side elevation of the respective couplings, &c.

A A' may represent portions of the customary platforms of a pair of freight or other cars adapted for the reception of my improved appliances.

B B are abutments composed of one or more layers of wood and iron, and secured to the front of the platforms A A' by bolts in any suitable manner.

C C are metallic thimbles secured in the abutments B, as represented in Figs. 1 and 3, for the reception of the stems b of the buffers D and their surrounding springs E. The stems d have an enlarged (if preferred, tubular) portion, d', which fits snugly the interior of the thimbles C, as shown, and their contracted portions pass through central apertures, c, in the bottoms of said thimbles, the abutment, &c., being cut away behind them sufficiently to allow of the requisite amount of movement.

The buffers D may be constructed as represented in Figs. 1 and 3 and their stems d secured to them as shown in those figures, or in

any other suitable manner. Their ends have rigidly secured to them guide or stay rods F, which, passing through the abutments and sills of the platforms, as shown, are screw-threaded and provided with nuts f, by which the degree of movement of said buffers may be regulated.

G G' H H' represent, respectively, pairs of jaws or coupling-bars on the cars A and A', respectively. These bars are pivoted at g and h to bars I and J, which are secured to the customary draw-springs in the usual manner. They (the bars G H and G' H') are respectively constructed with barbed heads g' and h' and hook-heads g'' and h'', which engage with each other, as shown in Fig. 2, in such a manner as to entirely preclude the possibility of uncoupling by any distortion of the position of the cars. The jaws are pressed together by springs K L and opened by cams M on vertical shafts N, which are pivoted at their lower ends in hangers O, which also support the loose ends of the coupling-jaws, and above the coupling-jaws in brackets a at the top of the car, as shown, when used on a freight-car, or in suitable bearings at the floor of the platform or other convenient point for the same or other styles of cars. Hand-wheels N' are provided on the upper ends of the shafts N, by which to rotate said shafts, and arms n n' project from them at about right angles at any convenient point for the purpose of holding the cams in their different positions. Brackets P P' are provided in suitable positions to receive the arms n n', and the upturned ends of said arms may form the handles by which to operate the said shaft.

Pins Q and R project from the under sides of the coupling-bars G and H, and bent levers S project from the lower end of the shafts N at such an angle relatively to the cams M that when the jaws are held open by said cams said levers shall so project as to engage with the pin on the bar of the other car to such an extent as to return the cam and allow the jaws to close, each car thus in separating resetting the coupling of the one to which it had been coupled.

Having thus described my invention, the following is what I claim as new and desire to secure by Letters Patent:

1. The combination of the hinged jaws or

bars G G' H H', the spring draw-bars I J, springs K L, and cams M, all constructed, arranged, and operating as described, for the purposes specified.

2. The combination, with the cams M for operating the spring-couplings G G' and H H', the arms n n' for holding said cams in their different positions, and the pins Q R and cam-arms S for returning the couplings to their closed position as the cars separate, all arranged and operating substantially as described.

3. The buffers D, stems d d', thimbles C, springs E, and rods F, all constructed and arranged substantially as described, and employed in combination with a self-locking car-coupling, for the purpose set forth.

To the above specification of my improvement in car-couplings I have signed my hand this 18th day of May, A. D. 1868.

DAVID S. BEALS.
